UNITED STATES PATENT OFFICE.

THOMAS P. FORD, OF BROOKLYN, NEW YORK.

ELEVATOR.

1,223,950.

Specification of Letters Patent. Patented Apr. 24, 1917.

Application filed November 25, 1916. Serial No. 133,323.

To all whom it may concern:

Be it known that I, THOMAS P. FORD, a citizen of the United States, and a resident of the city of New York, borough of Brooklyn, in the county of Kings and State of New York, have invented new and useful Improvements in Elevators, of which the following is a full, clear, and exact description.

10 The object of the invention is to provide certain new and useful improvements in elevators, arranged to prevent the operator of the car from starting the latter after stopping at any one of the landings unless both 15 the shaft door and the car door are in closed position, thus insuring safety to the passengers going in and out of the car.

In order to accomplish the desired result, use is made of a locking device for the controlling mechanism of the car to lock the 20 controlling mechanism at the time the car is at a standstill at a landing and the car door and the shaft door are both open, the said locking device moving bodily sidewise with 25 the said car door and being adapted to move transversely when released by the said shaft door to partly disengage the said locking device from the controlling mechanism on closing the shaft door, and to completely 30 disengage the locking device from the controlling mechanism on closing the car door.

A practical embodiment of the invention is represented in the accompanying drawings forming a part of this specification, in 35 which similar characters of reference indicate corresponding parts in all the views.

Figure 1 is an enlarged sectional side elevation of the elevator showing a car at the landing and with the car door and the shaft 40 door in open position and the controlling mechanism of the car locked against movement;

Fig. 2 is a similar view of the same with the car door and the shaft door in closed position and the controlling mechanism unlocked and in running position;

Fig. 3 is an enlarged side elevation of the controlling mechanism, the locking device and a portion of the car door to which the 50 locking device is attached, the controlling device being in locked position;

Fig. 4 is a sectional plan view of the same on the line 4—4 of Fig. 3;

Fig. 5 is a similar view of the same with 55 the shaft door closed and the car door open;

Fig. 6 is a similar view of the same with

both the shaft door and the car door closed; and

Fig. 7 is a similar view of the same with the car door closed and the shaft door open. 60

The up and down movement of the elevator car 10 in the shaft 11 is controlled by the usual controlling device 12 having a disk 13 provided with a handle 14 under the control of the attendant of the car 10 to start 65 and stop the car in the usual manner. The disk 13 is provided with a slot 15 which extends horizontally on the right-hand side of the landings. The car 10 is provided with a door 16, preferably in the form of 70 a gate of the lazy tong type, and mounted to slide, to open and close the car door opening 17, and which latter is adapted to register with a similar opening 18 at each landing 19. The opening 18 is adapted to be 75 opened and closed by an elevator shaft door 20 adapted to be moved into open or closed position in the usual manner by the attendant of the car.

In order to prevent the controlling disk 80 13 from being turned from normal stopping position into running position at the time a car is at rest at a landing and both or either door 17 or 20 is in open position a locking device is provided presently described in detail. The locking device consists essentially of a bolt or projection 85 25 adapted to engage the slot 15 and the said bolt 25 is attached at its back to the free end of a spring arm 26 secured to one of the 90 lazy tong members 27 of the car door 16. The lazy tong member 27 is preferably the one next the fixed member of the door 16 so that when the latter is moved into an open position the member 27 moves a short 95 distance but a distance sufficient to move the front end 28 of the bolt 25 out of engagement with the slot 15. The spring arm 26 is provided with a hump 29 adapted to be engaged by a fixed member 30 of the 100 shaft door 20 at the time the shaft door moves into open position to cause the spring arm 26 to move inwardly with a view to engage the bolt 25 with the slot 15.

The bolt 25 is provided on its left-hand side with an enlargement 31 which remains in engagement with the slot 15 at the time the bolt 25 is moved from the left to the right on closing the car door 16, but when the shaft door 20 is moved into closed position then the member 30 thereof disengages the hump 29 and allows the spring

arm 26 to swing back by its own resiliency to normal position thus disengaging the enlarged portion 31 from the slot 15.

The operation is as follows:

- 5 Presuming that the car 10 is reaching a landing and is stopped by the attendant of the car turning the disk 13 to stopping position so that the slot 15 extends horizontally, as previously explained: Now, when 10 the operator opens the car door 16 then the bolt 25 is moved to the left and engages with its free end 28 the slot 15 so that the disk 13 is locked against turning as long as the car door 16 is in open position. When 15 the attendant next opens the shaft door 20 then the member 30 thereof moves in engagement with the hump 29 and in doing so swings the arm 26 inward to engage the enlarged portion 31 of the bolt 25 with the 20 slot 15. When the attendant intends to start the car it is necessary for him to close both the shaft door 20 and the car door 16. When the attendant closes the shaft door 20 then the member 30 thereof moves out 25 of engagement with the hump 29 to allow the spring arm 26 to move outward until the enlarged portion 31 of the bolt 25 is out of engagement with the slot 15 but the free end 28 of the bolt 25 is still in engagement 30 with the slot 15 (see Fig. 5). When the attendant next closes the car door 16 then the bolt 25 is moved bodily from the left to the right until the free end 28 is out of engagement with the slot 15 (see Fig. 6). 35 The disk 13 is now unlocked and the attendant can turn the same to start the car.

In case the attendant should forget to close the shaft door 20 and only close the car door 16 then the bolt 25 is moved from 40 the left to the right until its free end 28 clears the slot 15 but the enlarged portion 31 still engages the slot 15 (see Fig. 7) and thus prevents the disk 13 from being turned.

It is understood that as long as the shaft 45 door 20 is in open position the bolt 25 is held in inward position by the action of the shaft door member 30 engaging the hump 29.

From the foregoing it will be seen that by the simple means described, the car after 50 having been stopped at a landing cannot be started unless both the shaft door 20 and the car door 16 are in closed position, thus insuring safety to the passengers going in or out of the car.

55 Having thus described my invention, I claim as new and desire to secure by Letters Patent:

1. In an elevator, the combination of a car, a car-controlling mechanism therefor, 60 a shaft door, a car door, and a locking device for the said controlling mechanism, the said locking device having means to lock the controlling mechanism at the time the

car is at a standstill at a landing, and the car door and the shaft door are open, the 65 said locking device being attached to the said car door to move bodily sidewise with the car door on opening and closing the latter, the said locking device and the said shaft door having coacting means to hold 70 the locking device in locking position while the shaft door is open and to allow the locking device to move transversely into a partly unlocking position relative to the said controlling mechanism on being released by the 75 shaft door on closing the latter, the said locking device being completely disengaged from the controlling mechanism on closing the car door.

2. In an elevator, the combination of a 80 car having a car door, a shaft door, a car-controlling mechanism, and a bolt engaging the said car-controlling mechanism at the time the car is at a landing and the said car door and the said shaft door are open, the 85 said bolt being carried by the said car door to move bodily with the car door on opening and closing the latter, the said bolt and the said shaft door having coacting means to move the bolt transversely in one direction and the said bolt having means to move it transversely in the opposite direction on being released by the shaft door on closing the latter.

3. In an elevator, the combination of a 95 car, a car-controlling mechanism for the same, a shaft door, a car door, and a bolt adapted to engage and lock the said controlling mechanism, the bolt having a spring arm attached to the said car door to move 100 the said bolt sidewise on opening and closing the car door, the said bolt being capable to move transversely in one direction by the resiliency of its spring arm and the said spring arm of the bolt and the said shaft 105 door having coacting means to move the bolt transversely in the opposite direction on closing the said shaft door, the said bolt being held in locking position by the coaction of both the car door and the shaft door 110 at the time the doors are in open position and the said bolt moving into open position and out of engagement with the said controlling mechanism on the closing of both doors.

4. In an elevator, a car-controlling mechanism for the car and having a disk provided with a slot, a bolt having a shoulder and adapted to engage the said slot, and a spring arm carrying the said bolt and attached to the car door to move sidewise with the latter, the said spring arm having a hump adapted to be engaged by the shaft door.
